ASSEMBLING MACHINE

Angelo Perri, Groveland, Mass., assignor to
Montreal Shoe Machinery Co., Ltd., Montreal,
Quebec, Canada, a corporation of Canada

Application November 1, 1939, Serial No. 302,378

8 Claims. (Cl. 12—4)

This invention relates to machines for assembling the upper, counter and lining of a shoe with the insole on a last preparatory to the pulling over and lasting operation, the parts being held in position by tacks which are driven thru the flange of the upper into the insole at the heel end and into the last at the middle of its back, by this operation.

In machines of this type the last is placed on a jack post which swings forwardly and rearwardly and the parts of the upper are placed in position on the last and the post is swung rearward to carry the last into position, to permit the tack driving operation to be performed. Before the tacks are driven the parts of the upper should be fitted as closely as possible to the last and the flange turned over onto the insole.

The primary object of my invention is to provide improved means of fitting the upper, counter and lining to the last, so that they will be drawn closely about the heel end of the last and pressed against approximately the entire surface of the heel part before the tacks are driven for holding these parts in position.

I accomplish this object by providing two pairs of oppositely disposed press rolls which press the parts of the upper firmly against the sides of the heel part of the last and are moved longitudinally of the last so as to draw the upper parts firmly against the heel end, so that the entire heel portion will be shaped to the last and held closely against the heel part thereof at the time the tacks are driven.

For a more complete disclosure of my invention reference is now made to the following specification in connection with the accompanying drawings in which:

Fig. 1 is a side elevation of an assembling machine containing a preferred embodiment of my invention.

Fig. 2 is a front elevation thereof.

Fig. 3 is detail plan view of the pressing and wiping means.

Fig. 4 is a sectional view at line 4—4 of Fig. 3.

Fig. 5 is a detail sectional at line 5—5 of Fig. 3.

Fig. 6 is a detail sectional view of the flange tackers.

Fig. 7 is a plan view of the pressing and wiping means in an advanced position.

Fig. 8 is a detail sectional view at line 8—8 of Fig. 7, illustrating the action of the press rolls.

Fig. 9 is a detail sectional view illustrating the position of the tackers.

The machine in which my invention is embodied

is of the common type illustrated in Knowlton Patent #1,671,430 of May 29, 1928.

As shown in the drawings, a jack post 10 is slidably mounted in a casing 12, which is mounted on a fixed pivot 14. An angular shaped link 16 is connected by pivot 18 at one end to a coupling 19 on the front end of a rod 20, and at its opposite end by pivot 22 to the casing 12. Rod 20 has a sleeve 24 thereon and a spring 28 on rod 20 is interposed between sleeve 24 and a sleeve 30, also on rod 20. A lever 32 is pivoted at its upper end to the frame by pivot 34 and its lower end is connected by pivot 36 to one end of a link 38, which is connected to sleeve 24 at its opposite end by pivot 40. Lever 32 has an arm 33 which engages a cam on the cam shaft 42. A lever 44 is pivoted at its lower end, by pivot 45, to a sleeve 46, which is fixed on the rear end of rod 20, and said lever 44 is mounted at its upper end on a fixed pivot 48, and has an arm 50 fixed thereon, which is arranged to operate a clutch 52 which connects the main shaft 54 with the cam shaft 42, so that, when arm 50 is swung downward, the clutch automatically connects shaft 54 to cam shaft 42. An arm 56 is also fixed on lever 44 and has a roll 57 which is engaged with a cam 58 on shaft 42.

With the above described construction, when the jack post is pushed rearward by the operator, it engages the front end of coupling 19 on rod 20 and forces the rod rearward, thereby causing lever 44 to be swung rearward on its pivot 48 and swinging arm 56 and also clutch arm 50 downward, so that the clutch 52 automatically connects shaft 54, which is power driven, to cam shaft 42, thereby immediately causing cam 58 to be rotated. The downward movement of arm 56 moves roll 57 out of the depression in cam 58, so that, as soon as the cam shaft starts to rotate, roll 57 will be engaged by the circular portion of cam 58, and during the remaining portion of the revolution of the cam shaft, arm 56 will be held in its depressed position by the cam, thereby holding lever 44 and locking rod 20 in the rearward positions into which they were pushed by the operator and locking the jack in its rearmost position. The inward movement of the jack post by the operator also swings arm 16, so that a shoulder 17 at its lower end engages the casing 12 in which the jack post is held, with the result that the latter is also locked in the position to which it was pushed by the operator, during the remainder of the operation.

The lower end of jack post 10 rests on a foot piece 60, which is mounted on a fixed pivot 61.

and a wedge 62 is supported on a frame portion 63 and is connected, by pivot 64, to one end of a lever 65, which is pivoted at 66 on foot piece 60. The opposite end of lever 65 is connected by pivot 67 to a flat rod 68 having two projecting shoulders 69 and 70 thru which a rod 72 passes and is slidable therein. A spring 73 is mounted on rod 72 between said shoulders and a collar 74 is secured on the rod 72 in engagement with the lower end of said spring. Rod 72 is connected at its upper end to a one end of a cam lever 76, which is pivoted at 75 at its opposite end and engages a cam on shaft 42 at an intermediate point, the arrangement being such that, after the jack post has been locked in its rearmost position, rod 72 is pulled upward, and, acting thru spring 73, rod 72 and lever 65, wedge 62 is forced forward thereby forcing foot piece 60 upward and causing jack post 10 to be forced upward also. This movement takes place subsequent to the wiping and pressing operations hereafter described.

A casing 78 is fixed on the frame and has a bar 79 slidably mounted therein. A wiper 80 is pivoted at 81 on a lug 82 on bar 79 and extends forwardly towards the position of the jack post when locked in its rearmost position. A lever 84 is mounted, at an intermediate point therein, on a fixed pivot 85 and is connected, at its lower end, to sleeve 30 by a pivot 86, and at its upper end, by a link 87, to the rear end of sliding bar 79. When the cam shaft is rotated, lever 32 is swung rearward causing link 38 to pull sleeve 24 rearward also and causing spring 28 to push sleeve 30 rearward and thereby swing the upper end of lever 84 forward, so that bar 79, which carries the wiper, is pushed forward.

A rod 90 is slidably mounted in bar 79 and is pressed forwardly by spring 91 therein (Fig. 4) and a Y-shaped centering device 92 is pivotally mounted on the front end of rod 90 directly beneath wiper 80. A supplemental centering device 93 is also provided beneath device 92. These parts perform their usual function of correctly positioning the last.

After the jack post, having a last, with an insole thereon and having the upper, counter and lining wrapped about the heel end of the last, has been pushed back into position and locked, as previously described, the wiper 80 is advanced by the forward movement of bar 79 and wipes the edge portions of these parts onto the heel of the insole, and at the end of this movement the jack post will be pushed up by wedge 62, so that the flanged or wiped in portions will be pressed firmly down onto the heel of the last. The rear end of the wiper is pressed upward by a stiff spring 88, so that a slight upward yielding of the wiper is permitted.

No claim is made for the portion of the machine thus far described except in combination with parts now to be described.

A pair of pressing devices are mounted on the front end of bar 79, at opposite sides of the wiper 80, comprising a pair of levers 94 mounted on pivots 95, so that they swing horizontally to and from the last. The rear ends of said levers are connected by a spring 96, which acts to swing the front ends thereof away from each other when in their rearmost position. Rolls 97 are mounted on the rear ends of levers 94 and arranged to engage fixed cam faces 98 on opposite sides of casing 78, so that when sliding bar 79 is pushed forward the front ends of levers 94 will be swung towards each other.

The front ends of levers 94 are each provided with pressing devices which are identical in construction and disposed in opposite relation. Each lever has a transverse guide way 99 in which a carrier 100 is slidably mounted, said carrier being rectangular in cross section and being held in its guide way by a cap plate 101. A longitudinal slot 102 is formed in each carrier thru which a post 103, fixed in its lever 94, passes, and a spring 104 is interposed between each post and the front end of the slot and acts to push the carrier towards the jack post. A stop screw 105 in the outer end of each carrier engages post 103 and limits this movement. The inner end of each carrier has a pair of ears 106, between which a support 107 is mounted on a horizontal pivot 108, and each support has a bearing 109 projecting downwardly therefrom and a bearing 110 projecting upwardly therefrom, on which press rolls 111, 112 are freely rotatable, respectively, each bearing 109 normally extending towards the jack post at a slight inclination from the vertical as it extends downward and each bearing 110 extending at a similar inclination from the vertical, as it extends upward, as shown in Figs. 5 and 8. An equalizing spring 113 is interposed between the front end of each carrier 100 and its support 107 and normally acts to hold the latter in the position of Fig. 5, but permits tilting movement thereof in either direction, which movement is limited by engagement of the support with the front end of the carrier.

The lower rolls 111 are slightly convex longitudinally, and the upper rolls 112 are slightly concave longitudinally. All the rolls are rounded at their ends and they all may be made of any suitable material as wood, hard rubber, or metal.

With the above described construction, when the jack post is pushed in to the position in which it is locked, the lower rolls 111 engage the opposite sides of the last in the slightly concave portion, approximately midway between its top and bottom, and press the upper, counter and lining thereagainst, the rolls tilting on their pivots 108 to conform to the inclination of the sides of the last. The upper rolls 112 will also be pressed against the slightly convex portion of the last closely adjacent the bottom of the last, so that the top ends of said rolls terminate at the level of the top surface of the insole which has been secured on the last bottom, as best shown in Fig. 8. As a result the upper parts will be pressed firmly against the sides of the last from top to bottom of its heel part.

As the sliding bar 79 is pushed forward, the rolls 111, 112 will not only press the parts on the last firmly against its sides thereof, but will also act to pull the upper parts firmly against the back of the last, the rolls being moved from the dotted line position of Fig. 7 to the full line position thereof.

The pressing and pulling action of rolls 111, 112 takes place simultaneously with the wiping action of the wiper 80, so that when the tacking operation takes place to secure the parts in position, these parts will have been tightly drawn against and effectively fitted to the heel portion of the last.

The tacking operation which then takes place is the same as in prior machines of this type, a tacker nozzle 114 being arranged to drive two tacks thru slots 83 in the wiper, to secure the wiped in flange to the insole, as indicated in

5 Figs. 6 and 9. A tacker nozzle 115 is also arranged to drive a single tack thru the back of the upper parts into the back of the last at the same time. As these tacking devices are well known in the art and constitute no part of my invention a detailed description thereof is thought to be unnecessary.

10 With the above described construction the parts of the upper are made to conform closely to the sides of the heel part of the last and are drawn tightly about the heel end thereof so that they are placed in the relation thereto that they are designed to be placed when the shoe is finished. This operation is also performed with 15 out injury to the upper, as the rolls work the upper onto the last without any sliding action thereon. The action approximates to what it would be when the operator attempts to fit these parts to the last with his hands, but the increased 20 force provided by the machine makes the operation more effective than is possible by hand.

I claim:

25 1. In a machine for securing parts of a shoe upper in assembled relation upon a last preparatory to lasting having, in combination, tackers, a jack arranged to carry the last with the parts of the shoe on the heel part thereof into position to be operated on by the tackers and means for locking the jack in said position, a pair of rolls 30 rotatably mounted at opposite sides of the last, when in said position, and means for moving said rolls into engagement with the sides of the heel part of the last and for then moving them towards the forepart thereof after the jack has 35 been locked, to conform the parts closely to the last before they are secured by the tackers.

40 2. In a machine for securing parts of a shoe upper in assembled relation upon a last preparatory to lasting, having in combination, tackers, a jack arranged to carry the last with the upper parts on the heel part thereof into position to be operated on by the tackers and means for locking the jack in said position, a pair of pressing devices arranged to engage opposite sides of the 45 heel part of the last when in said position, each comprising a pair of rolls mounted to rotate about axes transversely of the last when in said position, and means to move said rolls transversely of their axes towards the toe end of the last while 50 engaged therewith to conform the upper to the heel end of the last in advance of the operation of the tackers.

55 3. In a machine for securing parts of a shoe upper in assembled relation upon a last preparatory to lasting having in combination, tackers, means to hold the last with the shoe parts thereon in position to be operated on by said tackers, a pair of pressing devices disposed at opposite sides of the last when the last is in said position, 60 each comprising a pair of press rolls mounted to rotate about axes disposed transversely of the last, two of the rolls of each pair being arranged to press the upper parts against an intermediate portion of the opposite sides of the last and the 65 other two to press the parts against the side-portion of the last adjacent its bottom, and means to move the rolls while engaged with the last away from its heel end, prior to the operation of the tackers.

70 4. In a machine for securing parts of shoe uppers in assembled relation upon a last preparatory to lasting, having, in combination, tackers, means to hold the last with the shoe parts thereon in position to be operated on by said tackers, a pair of pressing devices disposed at opposite

sides of the last when in said position, each having a pair of rolls mounted to rotate about axes disposed transversely of the last, one of the rolls of each pair being arranged to engage the side of the last and the other rolls of the pair being arranged directly above the side engaging rolls and arranged to rotate about axes inclined towards each other and in position to engage the sides of the last adjacent its bottom and means for moving the rolls away from the heel 10 end of the last while engaged therewith in advance of the operation of the tackers.

15 5. In a machine for securing parts of a shoe upper in assembled relation upon a last preparatory to lasting, having in combination, tackers, means to hold the last with the shoe parts thereon in position to be operated on by said tackers, a pair of pressing devices disposed at opposite sides of the last when the last is in said position, each comprising a pair of press rolls mounted 20 to rotate about axes disposed transversely of the last, yieldable means for pressing said rolls against the sides of the last and means to move the rolls while engaged with the last towards the toe-end thereof prior to the operation of the 25 tackers.

30 6. In a machine for securing parts of a shoe upper to a last in assembled relation preparatory to lasting, having in combination, tackers, a jack for holding a last thereon in position to be operated on by the tackers, a support mounted to slide towards and from the heel end of the last when in said position, a pair of levers mounted on said support and extending forwardly therefrom and arranged to swing horizontally towards 35 opposite sides of the last, a spring actuated carrier in the front end of each lever mounted to slide transversely thereof, a holder mounted on a horizontal pivot on the end of each carrier, bearings projecting upwardly and downwardly, respectively, from each holder, rolls mounted on said bearings, means to advance said support towards the last, and means to swing said levers to press said rolls against the sides of the last as the support is advanced to press the upper 40 against the last and draw it onto the heel part in advance of the operation of the tackers.

45 7. In a machine for securing parts of a shoe upper to a last in assembled relation preparatory to lasting having in combination, tackers, means to hold the last in inverted position with the parts on the heel portion thereof in position to be operated on by the tackers, a support mounted to slide longitudinally of the last, when in said position towards and from the heel end thereof, 50 a pair of levers pivoted on said support and having rolls on the front ends thereof arranged to engage opposite sides of the last when in said position, a wiper on said support arranged between said levers in position to wipe the flange 55 of the upper parts onto the last at the heel end thereof, and means to advance said support towards the last and simultaneously press said rolls against the sides thereof, thereby to draw the parts onto heel end of the last as the flange there- 60 of is wiped in by the wiper.

65 8. In a machine for securing parts of a shoe upper in assembled relation upon a last preparatory to lasting, having in combination, tackers, means to hold the last with the shoe parts thereon in position to be operated on by said tackers, a pair of pressing devices disposed at opposite sides of the last when the last is in said position, each comprising a pair of press rolls mounted 70 to rotate about axes disposed transversely of the

last, two of the rolls of each pair having a longitudinally convex surface and being arranged to press the upper against an intermediate portion of the opposite sides of the last, and the other two rolls having a longitudinally concave surface and being arranged to press the upper against

the side portions of the last adjacent the bottom of the last and to move them longitudinally thereof towards its toe-end prior to the operation of the tackers.

ANGELO PERRI.
